UNITED STATES PATENT OFFICE

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,293,374.

Specification of Letters Patent.

Patented Feb. 4, 1919.

Application filed May 3, 1918. Serial No. 232,309.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Stay-Bolt Structures; and I do hereby declare the following to be a full, clear, and exact description of the invention, such as 10 will enable others skilled in the art to which it appertains to make and use the same.

This invention relates to improvements in staybolt structures and more particularly to the devices which constitute the inclosed 15 bearing for the head of the staybolt,—the object of the invention being to provide a simple construction whereby quick and ready access to the head of the bolt will be facilitated without removing the parts, to permit 20 testing of the bolt.

With this and other objects in view, the invention consists in certain novel features of construction and combinations of parts as hereinafter set forth and pointed out in 25 the claims.

In the accompanying drawings, Figure 1 is a longitudinal sectional view showing an embodiment of my invention, and Fig. 2 is a transverse section on line 2—2 of Fig. 1. 30 1 represents a boiler sheet having an opening therein, the wall of which may be threaded for the accommodation of a sleeve or bushing 2. The inner end of this sleeve or bushing is provided with a tapering opening 3 for the accommodation of the neck portion 4 of a staybolt 5,—the latter having a rounded or spherical head 6. The sleeve or bushing 2 is formed with a seat 7 upon which the inner end of an annular member 8 on 35 a cap 9 rests. The annular portion 8 of the cap fits neatly within the bushing 2 and is provided interiorly with a curved face 10 which forms a bearing for the rounded or spherical head 6 of the staybolt. The peripheral portion of the cap 9 is made with a flange 11 (which may have an angular external configuration for the accommodation 40 of a wrench) and said flange 11 is provided with internal segmental shoulders 12 adapted to become disposed behind segmental shoulders 13 on the sleeve or bushing 2 when the cap is turned. The cap 9 is also

provided centrally with an opening 14 having a threaded wall to receive a threaded plug 15,—the purpose of which is to facilitate the mounting of the head of the stay- 55 bolt.

It will be seen that with my improvements the cap or closure also constitutes a bearing for the head of the staybolt and that normally the parts will be held in place by the engagement of the segmental lugs of the cap with the segmental lugs on the sleeve or bushing 2. By turning the cap so as to bring the segmental shoulders or lugs there- 60 on out of line with the segmental shoulders on the sleeve or bushing 2, the staybolt may be tested to determine whether or not it is broken by attempting to pry the cap from the sleeve or bushing. Such operation may 65 be performed by inserting a suitable tool under the flanged edge portion of the cap. Thus the bolt may be tested without the removal of any of the parts.

Having fully described my invention what 70 I claim as new and desire to secure by Letters-Patent, is:

1. In a staybolt structure, the combination with a sleeve or bushing, of a cap or closure having a part disposed within said sleeve or 75 bushing and constituting a bearing for the head of a staybolt, and interlocking means between said cap or closure and said sleeve or bushing.

2. In a staybolt structure, the combination 80 with a sleeve or bushing, of a combined cap or closure and bearing for the head of the staybolt, and means providing an interlocking connection between said cap and sleeve or bushing.

3. In a staybolt structure, the combination with a sleeve or bushing, of a cap having a portion seated within said sleeve or bushing and affording a bearing for a head of a staybolt, said cap having a peripheral portion provided with internal segmental shoulders and a sleeve or bushing having external segmental shoulders for coöperation with the internal segmental shoulders of the cap. 85 90 95

4. In a staybolt structure, the combination 100 with a sleeve or bushing, of a cap having a part mounted within said sleeve or bushing and providing a bearing for the head of the staybolt, said cap also having an opening

provided with a threaded wall, a plug closing said opening, said cap having a peripheral flange provided with internal segmental shoulders, and the sleeve or bushing having 5 external segmental shoulders to coöperate with the segmental shoulders of the cap.

In testimony whereof, I have signed this

specification in the presence of two subscribing witnesses.

ETHAN L. DODDS.
